PORTABLE ELECTRIC METAL MELTER

Application filed April 6, 1931. Serial No. 528,116.

This invention relates to devices for melting metals, and particularly to one adapted to be used in connection with the melting of small quantities of metal, such as gold, silver, or other alloys, such as are employed in dental work, the jewelry industry and other lines.

At present, such metals are melted by means of a flame torch of one kind or another. The heat thus imparted to a piece of metal is unevenly distributed, an oxidizing and texture changing action on the metal takes place; and if the metal is an alloy, its character is apt to be changed. Also, the cooling of a metal thus heated takes place unevenly and it is apt to be distorted out of the form to which it has been shaped or melted.

The principal object of our invention is to avoid the objectionable features incident to the present method of melting metals in the above named industries, by the provision of an electric hand torch so constructed, and so "hooked-up" to a source of ordinary lighting circuit, that the metal is heated evenly throughout and cools in the same manner, and no oxidizing of the metal or change of character of an alloy is had.

A further object of the invention is to construct the entire apparatus so that it is of a readily portable nature, and which can be connected to any ordinary light socket, or outlet.

A further object of the invention is to produce a simple and inexpensive device and yet one which will be exceedingly effective for the purpose for which it is designed.

These objects we accomplish by means of such structure and relative arrangement of parts as will fully appear by a perusal of the following specification and claims.

In the drawing similar characters of reference indicate corresponding parts in the several views.

Fig. 1 is a top plan view of our improved torch.

Fig. 2 is an end view of the same, in position to melt a small piece of metal.

Fig. 3 is a diagram of the electric circuit employed in connection with the torch.

Referring now more particularly to the characters of reference on the drawing, 1 denotes a cylindrical handle member of in-

sulation material, from one end of which a pair of rigid rods 2 and 3 project. These rods are spaced apart diametrically of the handle and are bent between their ends so that their outer ends are also spaced diametrically of the axis of the handle, but in a plane at right angles to their opposite end. This arrangement is plainly shown in Fig. 2.

At their outer ends the rods have sleeves 4, which are disposed so that their axial lines intersect some distance below the plane of the handle, said lines also preferably having a forward and downward slant to the point of intersection, as shown in Fig. 1. These sleeves carry short carbons 5, which are adjustably held in place by clamping screws 6. Heat radiating flanges 7 are mounted on and surround the rods close to the sleeves.

Rod 2 is turnable in the handle and adjacent the forward end of the latter is provided with a short outwardly projecting finger lever 8 and which works in a circumferential slot in the handle. By this means, said rod may be turned relative to the rod 3 by a finger of the hand grasping the handle, and the converging ends of the carbons may be moved closer to or further away from each other, as may be necessary.

The ends of the rods 2 and 3 which are disposed inside the handle are connected with flexible cables 9 to one pair of terminals of an adjustable step-down transformer 10. The wires 11 from the other terminals of the transformer are connected to a plug 12 of ordinary character which is adapted to co-operate with the socket of an ordinary light circuit 13. A hand-switch 14 is interposed in one of the wires 11, as well as a fuse F; a volt-meter 15 is connected across the cables 9. The transformer, its adjusting means, the meter and switch are all mounted as a compact unit in a portable container, indicated at 16, so as to readily move from one place to another. The cables 9 between the container and the handle 1 are enclosed in a flexible housing 17, and are of sufficient length to permit of convenient manipulation of the torch some distance from the container.

Similarly wires 11 outwardly of the container are of sufficient length to avoid the

necessity of said container being placed close to the connected socket.

The current transforming apparatus is arranged to transform the current from the standard 110-V light socket down to a relatively low voltage of from 4-V to 22-V, depending on the adjustment of the transformer, from 6-V to 10-V, being the average used; at the same time the amperage of 10 the light socket current is not interfered with and the entire output is available at the carbons.

In operation, the piece of metal 18 to be melted is placed on a small crucible 19 of a material having dielectric or non-conducting properties, such as fire clay or porcelain. With the current of course turned on, the torch is held in the hand and the movable rod is turned so that the points of the carbons 20 are relatively close to each other, depending on the size of the piece of metal to be melted. The carbons are then both brought into contact with the metal, and the latter being, of course, a conductor, the circuit is closed between the carbons and the metal is almost 25 instantly brought to the melting point. Forming as it does a carrying part of the circuit, the metal is heated evenly; the carbon points being adjusted relative to the size 30 of the piece of metal so as to engage same substantially at its opposite edges, in this manner practically the entire width of the metal is disposed between the carbon points.

The melting action is had by the direct contact and flow of the current through the metal, without the aid of oxygen, so that no oxidizing and consequent change of texture or character of the metal or alloy is had.

The reduced voltage of the current used in 40 the torch prevents the possibility of any arcing between the points, while permitting the entire high amperage heat value to be retained. The low voltage also avoids the possibility of any appreciable shock being imparted to the operator and renders the implement safe to handle.

From the foregoing description it will be readily seen that we have produced such a device as substantially fulfills the objects of 50 the invention as set forth herein.

While this specification sets forth in detail the present and preferred construction of the device, still in practice such deviations from such detail may be resorted to as do not form 55 a departure from the spirit of the invention, as defined by the appended claims.

Having thus described our invention what we claim as new and useful and desire to secure by Letters Patent is:

60 1. An electric metal-melting torch comprising a handle member, rods projecting in spaced relation from one end of the handle, circuit means connected to the handle ends of the rods, one of said rods being turnable 65 in the handle, members on the rods at their

outer ends for supporting carbons in converging relation to each other, and means applied to the turnable rod at the handle for turning the same to alter the angle of convergence of the carbons.

70 2. A structure as in claim 1, in which said handle turning means comprises a finger lever projecting radially from the portion of the turnable rod which is disposed within the handle, said handle having a slot extending 75 in a plane circumferentially of the rod and through which said lever projects.

In testimony whereof we affix our signatures.

ANGELO D'AMICO.
